(74) *Attorney, Agent, or Firm* — Kirton McConkie; Evan R. Witt(57) **CLAIM**

The ornamental design for a light pipe module, as shown and described.

DESCRIPTION

FIG. 1 is a front, top and left side perspective view of a light pipe module showing my new design;

FIG. 2 is a rear, bottom and right side perspective view thereof;

FIG. 3 is an exploded top perspective view of FIG. 1;

FIG. 4 is an exploded front elevational view of FIG. 1;

FIG. 5 is an exploded rear elevational view of FIG. 1;

FIG. 6 is an exploded left side elevational view of FIG. 1;

FIG. 7 is an exploded right side elevational view of FIG. 1;

FIG. 8 is an exploded top plan view of FIG. 1; and,

FIG. 9 is an exploded bottom plan view of FIG. 1.

The dot-dash broken lines define the boundary of the claim. The dash-dash broken lines illustrate environmental subject matter; all broken lines form no part of the claimed design.
